UNITED STATES PATENT OFFICE.

EDWARD J. COLBY, OF CHICAGO, ILLINOIS.

GAS-REGULATOR.

SPECIFICATION forming part of Letters Patent No. 398,881, dated March 5, 1889.

Application filed May 26, 1888. Serial No. 275,198. (No model.)

To all whom it may concern:

Be it known that I, EDWARD J. COLBY, a citizen of the United States, residing at Chicago, in the county of Cook and State of Illinois, have invented a certain new and useful Gas-Regulator, of which the following is a specification.

My invention relates to devices for regulating the outflow of fluids, and particularly illuminating-gases; and its object is to provide a convenient, cheap, and simple device whereby the increasing pressure of the gas in the supply-pipe will act to limit the discharge-aperture.

15 My invention is illustrated in the accompanying drawings, wherein Figure 1 is a vertical cross-section. Fig. 2 is a front view of the valve. Fig. 3 is a detail enlarged cross-section of the valve.

20 Like parts are indicated by the same letter in all the figures.

A is a supply-pipe.

B is a discharge-pipe; C, the valve receptacle or case.

25 D is a pipe within the case C, and having the side aperture, E.

F is a plate adapted to slide back and forth on top of the pipe D, resting at its sides against the ledge G.

30 H is a screw provided at one end with a head, which is held in the side of the pipe D, and at the other end with a thumb-piece, J, whereby it may be turned. The screw H passes through a screw-threaded aperture in the rear end of the plate F, so that by turning the screw H by means of the thumb-piece the plate F may be reciprocated along the top of the pipe D.

At the outer extremity of the plate F are 40 arms K K, in which is pivoted the rock-shaft L, from which depends the plate M. This plate is provided with the conically-shaped valve N, to pass into the aperture E, and also with the screw-threaded bolt O, which may engage the stop P to limit the inward motion of the plate M and valve N.

45 R R are arms upon the lower part of the pipe D, to which is pivoted the rock-shaft S. On this latter is fixed the swinging stop T, 50 provided below with an adjustable counter-

weight, U, and above with a curved edge, V, against which the lower end of the plate M rests.

The use and operation of my invention are as follows: When the gas enters through the pipe A into the case C, its only means of exit into the discharge-pipe B is through the aperture E. The action of the gas passing through the aperture E tends to cause the valve N to close into such aperture, and thus limit the discharge. As the pressure increases in the supply-pipe, and thus in the case C, its tendency is to cause the valve N to more nearly fill the aperture E. Thus the discharge-aperture is in inverse ratio to the pressure. The accuracy and sufficiency of this movement depend upon the delicate and careful adjustment. In the first place the plate M is very delicately suspended by the rock-shaft L, so as to give a very free movement to such plate. Again, the arrangement of the screw-rod H permits the position of the rock-shaft L to be very delicately adjusted. Again, the stop P and screw-bolt O permit a positive limit to the motion to be given. At its lower end the plate M is supported by the swinging stop T. This stop is very delicately suspended on the shaft S, so as to move freely. Its weight or resistance may be varied by moving the nut O on its lower end. Moreover, as will be seen by comparison of Figs. 1 and 3, the curved knife-edge V at each inward movement of the plate M bears against such plate at a different position. Thus in Fig. 1 it is bearing against said plate at a considerable distance above the lower end of such plate, while in Fig. 3 the pressure of such swinging stop is applied to the lower end of such plate, and therefore much nearer to the fulcrum of the stop, so that the inward motion of the plate M and valve N is increasingly checked as it progresses in its motion to close the aperture E.

The shape of the valve N and its weight are such as to cause the plate M, with the valve N, to immediately retreat from the aperture E when the pressure is decreased, and the stop P and bolt O properly adjusted will prevent the plate M from coming too near the mouth of the aperture.

Having thus described my invention, what

I claim, and desire to secure by Letters Patent, is as follows:

1. In a fluid-regulator, the combination of a discharge-pipe having an aperture with a flap - valve and adjustable plate to which such flap-valve is pivoted, so as to vary the normal distance of the valve from the aperture.
2. In a fluid-regulator, the combination of a discharge-pipe having an aperture with a flap-valve pivoted above and supported below by a swinging stop.
3. In a fluid-regulator, the combination of a discharge-pipe having an aperture with a discharge-valve pivoted above and supported below by a swinging stop provided with a curved bearing-edge, so that as the flap-valve moves toward the aperture its bearing-point approaches the fulcrum of such stop.
4. In a fluid-regulator, the combination of a discharge-pipe having an aperture with a flap-valve pivoted above and a swinging stop provided with an adjustable counter-weight.
5. In a fluid-regulator, the combination of a discharge-pipe having an aperture with a flap-valve and a swinging stop provided with a bearing-edge of such shape that as the flap-valve nears the aperture the bearing-place approaches the fulcrum of the stop, and also with an adjustable counter-weight, so that the power of the stop may be varied.
6. In a fluid-regulator, the combination of a discharge-pipe having an aperture with a flap-valve, a fixed stop, and a screw-bolt to engage such stop, so that the limit of approach of the flap-valve to the aperture may be fixed at will.
7. In a fluid-regulator, the combination of a discharge-pipe having an aperture with a flap-valve pivoted above to an adjustable slide and supported below by a swinging stop provided with an adjustable counter-weight to fix the power of the stop at will.

EDWARD J. COLBY.
